BY

INVENTOR.
DARWIN M. WOLF
A.B. Bowman
ATTORNEY

My invention relates to a holder for cakes of soap under use and also saves the soap by preventing waste and the objects of my invention are:

First, to provide a soap holder of this class which holds the cake of soap in such a position that it quickly dries and the water drains off the same;

Second, to provide a soap holder of this class that is so shaped and arranged that air can contact the soap on all sides, therefore providing for quick drying of the cake of soap on all sides;

Third, to provide a soap holder of this class in which the soap cake is easily and readily positioned in the proper position for quick drying;

Fourth, to provide a soap holder of this class which maintains the cake of soap in its proper angular position for quick drying;

Fifth, to provide a soap holder of this class that is so constructed and arranged that the water from the soap drains clear away from the cake of soap;

Sixth, to provide a soap holder of this class which may be made of a single piece of material;

Seventh, to provide a soap holder of this class which is so shaped and arranged that it forms a quick drying support for the bar of soap as it changes its shape, form and size by usage; and

Eighth, to provide a soap holder of this class which is very simple and economical of construction, efficient in its action and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawing and to the characters of reference thereon which form a part of the application in which:

Figure 1 is a side elevational view of my soap holder and saver showing a cake of soap positioned thereon by dash lines; Fig. 2 is a front elevational view thereof; Fig. 3 is an isometric view thereof and Fig. 4 is a side elevational view of the holder with a slightly modified form of support for the soap holder.

Similar characters of reference refer to similar parts and portions throughout the several views of the drawing.

My soap holder includes two spaced side members 1 and 2 and a back member 3 which connects the two side members at their back edges, as

will be apparent from the drawings. The side members 1 and 2 are provided with a relatively low portion intermediate its ends and with upwardly extending angular portions extending therefrom.

UNITED STATES PATENT OFFICE

2,325,293

SOAP HOLDER AND SAVER

Darwin M. Wolf, San Diego, Calif.

Application September 5, 1942, Serial No. 457,391

5 Claims. (Cl. 45-28)

shown best in Figs. 2 and 3 of the drawing. These side members and back may be made of a relatively thin plate of any kind of material—metal, plastic or the like, and the side members are preferably provided with flat lower sides 1a and 2a, straight front sides 1b and 2b and straight rear sides 1c and 2c, which integrally connect with the back 3 so that the members 1 and 2 are held in certain spaced relation to each other. The upper sides of the members 1 and 2 are provided with low intermediate portions 1d and 2d; then with a plurality of round pointed step-like portions 1e and 2e leading upwardly from the portion 1d to the front upper side. From these intermediate portions 1c and extending backwardly and upwardly are a plurality of spaced pointed portions 1f and 2f, it being noted that these back portions 1f and 2f extend upwardly on a greater angle because the back side 1c is considerably higher than the front side 1b so that when the cake of soap rests with the narrower side on the points 1e 2e, the long side rests on the points 1f 2f on an angle, as shown best in Fig. 1 of the drawing so that water will quickly drain off the cake over its entire area. The sides of the cake of soap will be exposed to the air.

In the form of holder shown in Figs. 1, 2 and 3, the holder is positioned on any flat surface for supporting the cake of soap.

In the modification shown in Fig. 4 of the drawing, the structure is the same as disclosed in Figs. 1, 2 and 3 except that the upper ends of each side member 1 and 2 is provided with an extended portion 4 which extends backwardly some distance and then downwardly with an extended portion 5, thus providing hooks for supporting the holder on the upper side of a washtub or any vertical support.

Though I have shown and described a particular construction, combination and arrangement of parts and portions and a certain modification thereof, I do not wish to be limited to this particular construction, combination and arrangement, nor to the modification, but desire to include in the scope of my invention the construction, combination and arrangement substantially as set forth in the appended claims.

Having thus described my invention, what I claim as new and desire to secure by Letters Patent is:

1. In a soap holder and saver of the class described, the combination of two spaced side members, each provided with a relatively low portion intermediate its ends and with upwardly extending angular portions extending therefrom

and means connected to one end of each side member for connecting said members in their spaced relation to each other.

2. In a soap holder and saver of the class described, the combination of two spaced side members each provided with a relatively low portion intermediate its ends and with upwardly extending angular portions extending therefrom and means connected to one end of each side member for connecting said members in their spaced relation to each other, said annular extending portions provided with a plurality of pointed portions with rounded extremity.

3. In a soap holder and saver of the class described, the combination of a box-like member provided with an open front, the upper edges of the sides provided with forwardly and backwardly upwardly inclined upper edges provided with rounded extremity pointed portions thereon, the rearward portions extending higher and at a greater angle than the forwardly extending portions and means extending backwardly and downwardly from the upper side of each of said sides for supporting said holder and saver.

4. In a soap holder and saver of the class de-

scribed, the combination of a box-like member provided with an open front, the upper edges of the sides provided with forwardly and backwardly upwardly inclined upper edges provided with rounded extremity pointed portions thereon, the rearward portions extending higher and at a greater angle than the forwardly extending portions.

5. In a soap holder and saver of the class described, the combination of a box-like member provided with an open front, the upper edges of the sides provided with forwardly and backwardly upwardly inclined upper edges provided with rounded extremity pointed portions thereon, the rearward portions extending higher and at a greater angle than the forwardly extending portions and means extending backwardly and downwardly from the upper side of each of said sides for supporting said holder and saver.
